UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

ORNAMENTAL SEAM FOR SEWED ARTICLES.

1,286,957.

Specification of Letters Patent.

Patented Dec. 10, 1918.

Application filed May 3, 1917. Serial No. 166,085.

To all whom it may concern:

Be it known that I, ALBERT H. DE VOE, a citizen of the United States, residing at Westfield, in the county of Union and State 5 of New Jersey, have invented certain new and useful Improvements in Ornamental Seams for Sewed Articles, of which the following is a specification, reference being had therein to the accompanying drawings.

10 This invention relates to an ornamental seam for sewed articles wherein the ornamentation is produced by an edge-portion of material which is formed at intervals with indented portions confined by binding 15 stitches to produce a scalloped effect such as disclosed in my prior Patent No. 858,161, dated June 25, 1907.

The object of the invention is to produce an improved seam of the class described 20 which will strongly resist deformation and which may be formed as a strong and durable finish at the edge of the body-fabric or as an ornamental tuck within the edges of the body-fabric.

25 With the above and other objects in view, as will hereinafter appear, the invention consists of fabric material including a plurality of superposed portions and a folded edge-portion adjacent said superposed portions, which edge-portion is indented at intervals. A line of stitches is disposed adjacent said indented edge-portion. Certain of said stitches, preferably regularly recurrent ones, pass around the exposed edge of the 30 edge-portion at said indentations. A second line of stitches parallel with the first line passes through the fabric material at a distance back of the folded edge-portion and serves to secure an under ply of material to an 35 upper ply.

40 A better understanding of the invention may be had by referring to the accompanying drawings, in which Figure 1 illustrates the preferred embodiment of the invention, together with certain of the essential elements of a convenient mechanism by means of which the invention may be carried into effect. Fig. 2 is a vertical cross-section through the stitching point of Fig. 1. Fig. 45 50 55 3 shows a modification of the invention. Fig. 4 is a section on the line 4—4, Fig. 3.

As illustrated in the drawings the improved seam comprises fabric-material indicated generally by the numeral 1. In the modification shown in Fig. 1, the fabric-ma-

terial 1 includes an upper ply of fabric 2 having a folded edge 3. The fabric-material 1 further includes a lower ply 4 preferably in the form of a strip having outer and inner folded edge-portions 5 and 6, respectively. The folded edges 3 and 5 are superposed; that is, one is placed above the other. The fabric-material 1 further includes an ornamental edging-strip 7 which is preferably folded longitudinally along its center line and whose superposed edge-portions 8 are preferably inserted between the edges 3 and 5 and are therefore concealed by the plies 2 and 4. The exposed edge of the strip 7 is formed, preferably at regular intervals, with indentations 9. A line of stitches 10 disposed mainly in the fabric-material 1, parallel with and within the edges 3 and 5, serves to secure the upper and lower plies 2 and 4 to each other with the 60 edging strip 7 between them. Certain of said stitches, preferably, regularly recurrent ones, pass around the exposed edge of the 65 edging strip at 11 and bind in or confine the indented portions of the edging strip. 70 All of the stitches of the line 10, including the stitches 11, are anchored in the lower 75 ply or facing strip 4. A second line of stitches 12 parallel with the stitches 10 and relatively remote from the exposed edge of 80 the edging strip serves to secure the upper and lower plies 2 and 4 together and to conceal the inner edges of the edging and the 85 infolded edges of 3 and 5.

As shown in Fig. 1, the second line of 90 stitches 12 may be used for the purpose of stitching the inner folded edge 6 of the facing strip 4 to the upper ply 2 to neatly finish off the under side of the seam. The area between the lines of stitches 10 and 12 forms 95 a narrow band of uniform appearance which contrasts with the wavy or scalloped appearance of the edge of the article. This contrast enhances the ornamental appearance as 100 a whole. Any lateral strain to which the 105 edging 7 may be subjected is transmitted equally to the upper and under plies 2 and 4. For this reason the seam is not liable to be deformed by repeated laundryings or other harsh usage.

110 A convenient mechanism for carrying the invention into effect may comprise a pair of reciprocating needles 13 which coöperate with loop-taking means or loopers 14 to produce the spaced rows of stitches. The ma-

chine may be provided with the throat-plate 15 formed below its upper surface with a strip-guiding passageway 16 adapted to receive the folded strip 4 as it emerges from 5 the delivery end of the fold-guide 17 supported below the bed-plate 18. A second fold-guide 19, also disposed below the bed-plate, may be used to fold the edging strip 7 longitudinally and deliver it through an 10 opening 20 in the bed-plate to the upper side of the throat-plate along which it is led to the stitch-forming mechanism. The edge of the upper ply of material 2 may be passed through a suitable fold-guide, not shown, 15 and presented to the stitch-forming mechanism.

The machine may be equipped with a pair of grippers 21 and an edge indenter 22 disposed between said grippers 21 and formed 20 with a needle clearance recess 23. As the machine is operated, the material is advanced regularly by suitable feeding mechanism, such as fully disclosed in my said prior patent, while the needles produce straight- 25 away stitches. After a predetermined number of straightaway stitches have been formed the feed is arrested while the grippers are forced downwardly to hold the edging 7 at spaced points. The indenter 22 is 30 advanced longitudinally to deflect the portions of the edging 7 between the two grippers so that the right-hand needle in its next descent may pass down beside the indented edge-portion and through the lower 35 ply 4. After the needle rises the indenter is withdrawn and the grippers elevated to allow the distorted material to spring back under the right-hand needle 13. The feeding action is then resumed and succeeding straightaway 40 stitches are passed through the material followed by an overedge stitch, &c., as above described.

In the modification of the invention shown in Fig. 3 the fabric-material 1 is folded so 45 as to include superposed upper and under portions 2' and 4' of material. The fabric-material 1 may be said to further include an ornamental edge-portion 7' which is adjacent to and in this connection is integral with the 50 superposed portions 2' and 4'. The exposed edge of the edge-portion 7' is formed at intervals with indentations 9'. A line of stitches 10' serves to secure the superposed portions 2' and 4' together and certain of 55 said stitches pass around the exposed edge of the folded edge-portion 7 at the points 11' and bind-in or confine the indented portions 9'. The second line of stitches 12', parallel with the line of stitches 10' serves to 60 secure the superposed portions 2' and 4' together at a point relatively remote from the edge-portion 7'. In this modification, the superposed portions 2' and 4' together with the edge-portion 7' form an 65 ornamental tuck comprising a smooth base-

portion 7" of uniform appearance and the indented edge-portion 7'. During a laundrying operation the tuck, as a whole, may be caused to lie substantially flat by pressing a hot iron over the smooth base-portion 7". 70 The indented edge-portion 7' need not be subjected to the flattening action of the iron and therefore retains its normal soft and wavy appearance while lying close to the under-lapping ply of body-fabric. 75

Having thus set forth the nature of the invention, what I claim herein is:—

1. A seam for sewed articles comprising, in combination, a number of plies of fabric material, an edge portion thereon, a line of 80 stitches in said material adjacent the edge portion, spaced stitches in said line being drawn over the edge portion to form indentations therein, and a second line of stitches parallel with the first line, whereby an 85 anchorage is formed preventing distortion of the indented portion by strains transverse to the first line of stitches.

2. An article of fabric-material including, a folded edge-portion which is indented at 90 intervals, a line of stitches adjacent said edge-portion, certain of said stitches passing around and confining said folded edge-portion at the indentations therein, and a second line of stitches formed in said article 95 in parallelism with said first-mentioned line of stitches and relatively remote from said edge-portion, whereby distortion of the material at the first line of stitches is prevented. 100

3. A seam for sewed articles comprising, upper and lower plies of material presenting superposed edge-portions, an edging strip having an inner edge disposed between said edge-portions and an outer edge 105 which is indented at intervals, and a line of stitches serving to secure the parts in their above defined relative positions, certain of said stitches passing around and confining the indented portions of the edging strip. 110

4. A seam for sewed articles comprising, upper and lower plies of material presenting superposed edge-portions, an edging strip having an inner edge disposed between said edge portions and an outer edge which is indented at intervals, and a line of stitches serving to secure the parts in their above defined relative positions, certain of said stitches passing around and confining the indented portions of the edging strip, and an additional line of stitches parallel to said first-mentioned line and passing through 115 said upper and lower plies. 120

5. A seam for sewed articles comprising, a body-fabric presenting an edge, a facing strip applied to the under surface of said body-fabric adjacent said edge, an edging strip having an inner edge-portion disposed between said body-fabric and facing strip, and a line of stitches securing said parts, 125 130

spaced stitches in the line being drawn over the outer edge of the facing strip to form indentations therein.

6. A seam for sewed articles comprising, 5 a body-fabric presenting an edge, a facing strip applied to the under surface of said body-fabric adjacent said edge, an edging strip having an inner edge-portion disposed between said body-fabric and facing strip 10 and having an outer edge-portion which is indented at intervals, and a line of stitches serving to secure the parts in their above defined relative positions, all of said stitches being anchored in the facing strip and certain of said stitches passing over the outer 15 edge of the edging strip at the indentations therein and serving to confine said outer edge at said indentations, and a second line of stitches serving to secure the inner edge of the facing strip to the body-fabric.

7. A seam for sewed articles comprising, 20 a body-fabric presenting an edge, a facing strip applied to the under surface of said body-fabric adjacent said edge, an edging strip having an inner edge portion disposed between said body-fabric and facing strip 25 and having an outer edge portion which is

indented at intervals, and a line of stitches serving to secure the parts in their above defined relative positions, all of said stitches being anchored in the facing strip and certain of said stitches passing over the outer 30 edge of the edging strip at the indentations therein and serving to confine said outer edge at said indentations, and a second line of stitches serving to secure the inner edge of the facing strip to the body-fabric.

8. A seam for sewed articles comprising, 35 upper and lower plies of material presenting superposed edge-portions, an edging strip having an inner edge disposed between said edge-portions and an outer edge which is 40 indented at intervals, and a line of stitches passing mainly through said superposed edge-portions and the inner edge of the edging strip and including stitches which pass around and confine the indented portions of the edging strip.

In testimony whereof, I have signed my name to this specification.

ALBERT H. DE VOE.
